UNITED STATES PATENT OFFICE.

THOMAS A. WATROUS, OF WELLSBOROUGH, PENNSYLVANIA.

THILL-COUPING.

SPECIFICATION forming part of Letters Patent No. 242,085, dated May 24, 1881.

Application filed February 24, 1881. (Model.)

To all whom it may concern:

Be it known that I, THOMAS A. WATROUS, of Wellsborough, Tioga county, Pennsylvania, have invented a certain new and Improved 5 Thill-Coupling; and I do hereby declare the following to be a full, clear, and exact description of the same, reference being had to the accompanying drawings, forming part of this specification, in which—

10 Figure 1 is a top-plan view; Fig. 2, a side view, and Fig. 3 a sectional view taken on the line xx , Fig. 1.

Similar letters of reference in the several figures denote the same parts.

15 My invention consists of a safe and noiseless thill-coupling constructed as I will now proceed to describe.

Referring to the drawings, A represents a metal bed piece or plate adapted to be secured 20 to the under side of the axle B by means of a clip, C, and having shoulders a a , which fit against the axle in front and rear and greatly relieve the clip of strain. The ends of the clip may be riveted against the plate A, or screw-threaded and provided with nuts, as shown. 25 The forward part of the plate A is provided with lugs or side flanges, a^2 a^2 , between which is pivoted the eye d of an ordinary thill-iron, D, upon a cross-bolt, a^3 , that passes transversely through perforations in the lugs, as 30 shown in dotted lines, Fig. 1. Between the lugs or side flanges, and resting upon the part a^4 of the plate, is an elastic-rubber block, E. This rubber block is adapted to bear against and 35 partially overlap the eye of the thill-iron, as shown in Fig. 3, and it is held in place by a cap-plate, F, and a screw-bolt, G, which passes down through the cap-plate and the block and into a screw-threaded orifice, a^5 , in the lower plate.

40 The rubber block is of wedge-shaped form, being thickest at the end which bears against and overlaps the eye of the thill-iron, and tapering thence to the end nearest the clip, as shown in Fig. 3, and when inserted loosely in 45 place it projects slightly above the side flanges or lugs, a^2 a^2 , in order that when the cap-plate is forced down by the operation of the screw-bolt, G, the block will be compressed and expanded laterally, and caused to bear with increased pressure against the eye of the thill-

iron. The cap-plate F is provided with depending side flanges, f f , which embrace the lugs or side flanges, a^2 a^2 , of the lower plate, and hold the cap-plate from lateral displacement. The downward-turned extensions or 55 ends f' f' of the side flanges of the cap-plate cover, or partially cover, the ends of the pivotal cross-bolt a^3 when the cap is screwed down, so as to hold said bolt from working out and causing an uncoupling of the device. 60

It is, of course, desirable at times to take off the thills, and in order that this may be readily accomplished without entirely removing the cap plate I bevel or chamfer off the side flanges of the lower plate, as shown in dotted lines at 65 a^6 in Fig. 2, so as to enable the cap-plate, when the screw-bolt G is screwed out or loosened, to be tilted backward, as shown in dotted lines, until the ends f' f' of its side flanges are removed from the ends of the cross-bolt a^3 , when 70 the latter can be pushed out and the thill-iron released.

The perforation in the rubber block is preferably made a trifle smaller than the diameter of the screw-bolt G, which passes through it, 75 and the binding of the rubber on said bolt, in addition to the pressure of the cap-plate on the head of the bolt, is sufficient to effectually prevent the bolt from accidentally turning or working loose after being adjusted to position. 80

Inasmuch as the rubber block is entirely enclosed it is protected from dust, mud, and water, and cannot possibly become lost or accidentally displaced.

Thus constructed the coupling is strong, 85 noiseless, easily and cheaply made, not liable to get out of order, and, in fact, contains every desideratum of a first-class appliance of its kind.

Having thus described my invention, I claim 90 as new—

1. The combination of the lower plate, its flanges, the thill-iron, and the pivotal cross-bolt with the rubber block bearing against and slightly overlapping the eye of the thill-iron, the cap-plate having the side flanges, and 95 means for clamping down the cap-plate, substantially as described.

2. The combination of the lower plate, its flanges, the thill-iron, and the pivotal cross- 100

bolt with the rubber block, the cap-plate having the side flanges, and the extension of said flanges adapted to cover the ends of the pivotal cross-bolt, and with the screw-bolt G, for 5 clamping down the cap-plate, substantially as described.

3. The combination of the lower plate, having the side flanges beveled or chamfered, as described, with the wedge-shaped rubber block,

the cross-bolt, the thill-iron, and the cap-plate 10 and its clamping-bolt, whereby by loosening the clamping-bolt the cap-plate can be slightly tilted, so as to enable the cross-bolt to be pushed out, substantially as described.

THOMAS A. WATROUS.
